UNITED STATES PATENT OFFICE.

GEORGE A. WADSWORTH, OF MONTEVIDEO, MINNESOTA.

ADJUSTABLE STAND.

SPECIFICATION forming part of Letters Patent No. 704,603, dated July 15, 1902.

Application filed April 1, 1901. Serial No. 53,885. (No model.)

To all whom it may concern:

Be it known that I, GEORGE A. WADSWORTH, a citizen of the United States, residing at Montevideo, in the county of Chippewa and State 5 of Minnesota, (post-office address, General Delivery,) have invented certain new and useful Improvements in Adjustable Stands, of which the following is a specification.

The object of my invention is to provide a 10 vertically-adjustable stand designed for supporting cans, jugs, or other receptacles at any height under faucets or pumps.

To this end my invention consists in the 15 feature of construction and combination hereinafter specifically described and claimed.

In the accompanying drawings, forming part of the specification, Figure 1 is a side elevation of my improved supporting-stand, and Fig. 2 is a top view of the same.

20 A represents the base of the stand, preferably constructed, as shown, in the form of a metal ring having an inward bend 2 in the rear side to conform with the side of the pump or barrel. Secured to the opposite side 25 of the base-ring A is the standard B, formed on its outer edge with serrations or teeth 3.

C represents an adjustable support for the 30 jug or other receptacle, which consists of a ring secured in the casing 4, inclosing the standard B. The casing and ring C are held in adjusted position upon the standard by means of the dog 5, having fulcrum-support 6 and engaging at its lower end 7 with the teeth 3, the lower end of the dog being held 35 in engagement with the teeth by a spring 8, interposed between the upper end of the dog and casing. By turning the dog out of en-

gagement with the teeth the ring C can be carried to any desired position on the stand-ard, and by allowing the dog to be carried 40 into engagement with the teeth by the spring the ring will be held in such position.

My invention is especially designed for use in connection with emptying faucets or pumps of barrels. By means of the adjustable sup- 45 porting-ring C a jug or receptacle of any size can be brought up as close as desired to the mouth of the faucet.

I claim—

1. In a supporting-stand of the class de- 50 scribed, the combination with a vertical stand-ard, of two telescoping rings, one carried by the bottom to serve as a base for said stand-ard, and one slidably upon said standard, and means for holding said adjustable ring in ad- 55 justed position.

2. In a supporting-stand of the class de- 60 scribed, the combination of a vertical stand-ard, a ring carried by the bottom of, and forming a base for said standard, a casing 65 inclosing said standard, a ring secured to said casing upon one side of said standard, ser- rations carried by the opposite side of said standard, a dog having fulcrum-support upon said standard, with an inwardly-turned lower end adapted to engage with said serrations, and a spring interposed between the upper end of said dog and said casing.

In testimony whereof I affix my signature in presence of two witnesses.

GEORGE A. WADSWORTH.
